MORRIS GROSSMAN, OF NEW YORK, N. Y., ASSIGNOR TO MOLLIE GROSSMAN, OF
NEW YORK, N. Y.

COMBINATION NECKTIE AND HANDKERCHIEF DISPLAY FOLDER

Application filed November 27, 1931. Serial No. 577,627.

This invention relates to an improved combination necktie and handkerchief display folder, the object being to provide a simple and effective structure which is pleasing in appearance, whereby a necktie and a handkerchief may be held for display without injury thereto.

Another object of the invention is to provide a display device for handkerchiefs and neckties wherein a single handkerchief with a single necktie are mounted so as to be protected and yet displayed in such a way as to present a pleasing appearance of both the necktie and handkerchief while permitting ready examination of either.

A further object, more specifically, is to provide a display folder for displaying neckties and handkerchiefs wherein the parts are formed with slots and cutaway portions arranged to display both the necktie and handkerchief, and to hold the necktie and handkerchief in a folded position with part thereof positioned to be readily examined by a purchaser.

25 In the accompanying drawings—

Figure 1 is a front view of a display folder embodying the invention, the same being shown in connection with a handkerchief and a necktie, the folder being illustrated as resting on a support.

Figure 2 is a rear view of the folder shown in Figure 1.

Figure 3 is a vertical sectional view through Figure 1 on line 2—2, the same being on a greatly enlarged scale.

Figure 4 is a plan view of the folder shown in Figure 1 with the parts spread out and illustrating how the necktie is held in one portion or section of the folder and the handkerchief in another portion or section of the folder.

Figure 5 is a view similar to Figure 1 but showing a slightly modified construction.

Referring to the accompanying drawings by numerals, 1 indicates a shelf, table, or other support, which forms no part of the present invention, but merely is used in the drawing to indicate how the folder 2 may be supported to present the necktie in a vertical position. Folder 2 when resting on the sup-

port 1 must have something in the back to hold the same in the position shown in Figure 1, as for instance, a bracket or a carton or two. However, the position in which the folder is arranged is optional with the store-keeper. The folder 2 is illustrated in Figure 4 in an open position from which it will be seen, what might be termed, a back section 3, and a front section 4. The back section 3 is solid throughout except for slits 5 and 6, which are arranged as shown at the left in Figure 4, to present a strap 7 designed to hold the tongue 8 of flap 9 in position, as illustrated in Figure 2.

The folder may be made from any desired grade of paper, or other material, and preferably, from one sheet, so that the sections 3 and 4 will be integral but bent along the line 10. Section 3 is provided with what may be termed a body 11 having turned-in flanges 12, 13, and 14, which act to hold the handkerchief 15 in place. If the handkerchief 15 is of the proper size, it will fit beneath the flanges 12 to 14 inclusive, but if not a proper size, same must be folded until it fits, as shown in Figure 4. The section 4 is provided with what may be termed a body 16 which has openings or cut-out portions 17, 18, 19, and 20, whereby the diagonally arranged bars 21 and 22 are formed. The bar 22 at its juncture at the outer part of the body 16 is provided with slits 23 and 24 whereby the strap 25 is produced. An opening or slot 27 is arranged in the bar 22 at the inner section of bar 21, while near the end of bar 22 and opposite strap 26 is provided a strap 28 resulting from the slots 29 and 30. The necktie 31 is folded as shown particularly in Figures 3 and 4, and the small end passed through the slot 27, then through the slits 24 and 23, after which the small end is folded over the strap 26, and finally threaded through the slots 29 and 30 beneath the strap 28, thus causing the straps 26 and 28, and associated parts, to clamp the necktie in place while leaving the lower end 32 loose so that it may be lifted and readily inspected by a purchaser. The bar 22 is also provided with a cut-out 33 which is shaped as a four-in-hand tie after the same has been tied. Part of the

necktie 31 is seen through this cut-out, and as a collar 34 has been drawn on the bar 22, the effect is to show what the necktie will look like when actually tied and worn. By reason of the cut-out portions 17 to 20, the handkerchief is freely exposed for a large part of the surface and may be readily touched with the fingers, if desired. In case that closer or more thorough examination is desired, the tongue 8 may be slipped out of position, as shown in Figure 2, and then the parts 3 and 4 swung to the position shown in Figure 4. Both the necktie and handkerchief may then be removed, if desired, without injury to the goods or to the holder.

From Figures 2 and 4, it will be seen that the section 4 is provided with flanges 35 and 36, which are spread out before the section 3 is folded against section 4. After the sections have been folded together flanges 35 and 36 are then folded over the side edges of section 3, as shown in Figure 2, and finally the flap 9 is folded over, and tongue 8 inserted, thus locking the parts together with the necktie and handkerchief exposed to view, as shown in Figure 1. In this way, the necktie and handkerchief are both protected, and at the same time exposed to view in a very pleasing manner.

In Figure 5 a slightly modified construction is shown wherein the holder is formed identically as that shown in Figure 1 except it is provided with a slot 37 instead of the strap 26, and also provided with a strap 38 instead of the slot 27. By reason of this construction more of the necktie is exposed to view, but naturally the cut-out portion 33 and the collar 34 are not utilized.

I claim:

1. A combination necktie and handkerchief display folder including a pair of sections swingably connected together, one section being of the size and shape to fit flatwise against the other section, said other section having a plurality of flanges overlapping the first mentioned section to hold the same in folded position, means on the first section for retaining a handkerchief therein, and means on the other section formed to retain a necktie therein so that part thereof will be displayed, said other section having openings through which said handkerchief may be seen.
2. A combination necktie and handkerchief display folder including a pair of sections adapted to fit substantially flatwise against each other, one of said sections having handkerchief retaining flanges, and the other section having cut-a-way portions, whereby a bar is presented extending across the other section, and also whereby a handkerchief in the first mentioned section may be seen, said bar being provided with openings at a plurality of points whereby a necktie may be threaded therethrough and thereby held in

place, while at the same time exposing certain parts of the necktie, and means on said other section for retaining the two sections in their folded position.

3. In a display folder of the character described, a main section and an auxiliary section, said auxiliary section having a pair of slits therein near one edge whereby a retaining strap is presented, said auxiliary section being also provided with a plurality of flanges for retaining a handkerchief on said auxiliary section, said auxiliary section being adapted to be folded over against the main section, said main section being provided with openings therein, and means for retaining a necktie thereon, said auxiliary section being also provided with an extension acting as a tongue adapted to be inserted into said slits beneath said strap for locking the two sections together.

4. A display folder including a main section and an auxiliary section, means carried by said auxiliary section for holding a handkerchief thereon, said main section having a plurality of openings for displaying said handkerchief when the auxiliary section is folded against the main section, means carried by the main section for locking the auxiliary section in contact therewith, said main section having a pair of spaced straps and a central aperture whereby a necktie may be positioned to extend through said aperture and interlock with said straps so as to be held in position on said auxiliary section with part thereof exposed.

5. A display folder of the character described including a main section and an auxiliary section, said main section being provided with means for supporting a handkerchief, said auxiliary section being provided with a plurality of substantially triangular shaped openings whereby a cross shaped structure is presented, said cross shaped structure being provided with means for retaining a necktie thereon so that part thereof will be exposed to view, said handkerchief having certain parts thereof exposed through said openings, said main section having a pair of side flanges adapted to fold over the auxiliary section when the auxiliary section is folded against the main section, and means presenting a tongue interlocking with part of the auxiliary section for holding the same in a folded position, said last mentioned means overlapping said flanges for preventing unfolding thereof.

MORRIS GROSSMAN.
